Cornelius L. Campbell

UNITED STATES PATENT OFFICE.

CORNELIUS L. CAMPBELL, OF BINGHAMTON, NEW YORK, ASSIGNOR TO
WASHINGTON W. WHEATON, OF SAME PLACE.

IMPROVEMENT IN MACHINES FOR FITTING AXLE-SPINDLES TO SKEINS OF WAGONS.

Specification forming part of Letters Patent No. 58,714, dated October 9, 1866.

To all whom it may concern:

Be it known that I, C. L. CAMPBELL, of Binghamton, in the county of Broome and State of New York, have invented a new and useful Improvement in a Machine for Fitting Spindles of Axe-Trees for Wagons to Skeins or Thimbles; and I do hereby declare that the following is a full, clear, and exact description of the construction and operation of the same, reference being had to the annexed drawings, making a part of this specification, in which—

Figure 1 is a perspective view; Fig. 2, a transverse vertical section, showing the gear-reach. Fig. 3 represents the way or guide-plate detached; Fig. 4, a transverse vertical section of that end of the machine into which the reach is introduced.

Like letters represent like parts in all the figures.

The nature of my invention consists in fitting the spindles or arms of axle-trees for wagons to cast-iron skeins or thimbles by means of a revolving slide-cutter running obliquely to the axis of its mandrel, dispensing with the use or control of a pattern, and so arranged that it can be made light and portable and operated by hand, thus securing a more accurate fit and performing the operation in a more expeditious manner than by the ordinary mode, which is by means of the draw-shave and file.

I construct my machine of the material usually used for similar purposes. I make the frame A of cast-iron, its sides extending angularly from the annular collar O to near the end of the mandrel C. This end of the frame should be left broad enough for the bearing of the journal on the end of the feed-screw E, as this screw runs parallel with and about three inches from the mandrel, revolving around it, and at the same time rotating upon its own axle by means of the crank which is attached to the internal gear-driving wheel, as represented in Fig. 2.

The pinion F is stationary and attached to the gear-standard G. The pinion H on the end of the feed-screw revolves with it around the mandrel, and is held in position by the arm I, which is keyed to said mandrel.

The revolving slide-cutter J is operated by a hinged nut, K, and, after turning the re-

quired distance, it is detached and drawn back.

The way or guide-plate L is attached to the frame, and so arranged as to give the required size and angle to the work by means of two projections or arms, m m, from the frame. In these arms I make a slot of sufficient length to graduate the guide-plate L to any required size and angle of the spindle. Said guide-plate is secured in its position by means of screw-bolts.

The end of the machine into which the work is introduced is represented in Fig. 4. The standard B has a flange running around the circular opening, upon which the annular collar O and frame revolve. On the outside of said standard I make projections for set-screws for the purpose of centering and holding the work in its place. The working or gear end of the machine is supported by the standard G. The machine is now placed in position for operation by securing it to the bench.

When I use my improvement, I first prepare the axle-tree by drawing a line through the center of the shaft from end to end. I then ascertain the caliber of the skein or thimble, and lay out the proper angle and size of the spindle, giving it the required "gather" by throwing it a little out of line with the center of the shaft, commencing twelve inches (more or less) from each end. This variation is usually about one-eighth of an inch. The spindles are then prepared for turning by dressing them off to nearly the size and angle required. I then get the center on each end, and the work is ready for the machine. I now enter the end of the axle-tree through the annular collar O, and bring the center or the end in contact with the point of the mandrel C. I then adjust the set-screws to the work. I now set the way or guide-plate L to the proper angle and size of the spindle, then open the hinged nut K, and place the cutter J at the end of the spindle, and the machine is ready for operation, which is performed by means of the crank attached to the gear-driving wheel. The feed-screw is then caused to revolve around the mandrel, and at the same time to rotate on its own axle, by means of the stationary pinion F, and thus control the movement of the slide-cutter.

I do not claim the mere turning of the arms

or spindles of axle-trees for wagons to fit the box. Neither do I claim the revolving tapering cutter-head.

What I claim, and desire to secure by Letters Patent, is—

The manner of fitting the arms or spindles of axle-trees for wagons to cast-iron skeins or thimbles by means of the revolving slide-cut-

ter J, in combination with the adjustable way or guide-plate L, Fig. 3, the feed-screw E, and the hinged nut K, substantially as and for the purposes described.

CORNELIUS L. CAMPBELL.
